(57) **CLAIM**

The ornamental design for a matte box, as shown and described.

DESCRIPTION

FIG. 1 is a rear, right and bottom perspective view of a matte box showing our new design;

FIG. 2 is a front, left and top perspective view thereof;

FIG. 3 is a rear, right and bottom perspective view thereof, showing the matte box in a close configuration;

FIG. 4 is a front view thereof;

FIG. 5 is a rear view thereof;

FIG. 6 is a right view thereof;

FIG. 7 is a left view thereof;

FIG. 8 is a top view thereof;

FIG. 9 is a bottom view thereof; and,

FIG. 10 is an enlarged portion view taken from encircled portion labeled, “10” in FIG. 2.

The dashed-dot lines form the boundary of the enlarged portion view of FIG. 10 in FIGS. 2 and 10 and form no part of the claimed design. The even dashed broken lines shown in the drawings are included for the purpose of illustrating portions of the matte box that form no part of the claimed design.
